UNITED STATES PATENT OFFICE.

HARRY WALLACE LAWRENCE, OF DENVER, COLORADO.

FIXTURE FOR ADJUSTABLE ELECTRIC DROP-LIGHT

971,203.

Specification of Letters Patent. Patented Sept. 27, 1910.

Application filed June 14, 1909. Serial No. 502,145.

To all whom it may concern:

Be it known that I, HARRY WALLACE LAWRENCE, a citizen of the United States of America, residing in the city and county 5 of Denver and State of Colorado, have invented a new and useful Fixture for Adjustable Electric Drop-Lights, of which the following is a specification.

This invention relates to supporting fixtures for adjustable electric drop lights.

The object of the invention is to provide a fixture of this character, comprising a non-conducting plate or housing which is attached to the ceiling, and which is provided 15 with terminals to which the circuit feed wires are secured in the usual manner; and a non-conducting block secured to the said plate or housing, having terminals to which the lamp wires are attached, and which are 20 in circuit with the feed wire terminals, and a roller over which the said lamp wires travel, after passing down and around a similar roller on a counter-balancing weight, through which the free ends of the lamp- 25 wires pass, the said wires being connected to an electric drop light, the arrangement of lamp wires and rollers being such as to permit a vertical adjustment of the drop light.

The invention further consists in certain 30 details of construction hereinafter to be set forth, and illustrated in the accompanying drawings, in which:

Figure 1, is a side view of the fixture, the 35 two parts constituting the same being connected. Fig. 2, is a bottom plan view of the same. Fig. 3, is a bottom plan view of the ceiling plate, showing the feed wire terminals and wires connected therewith. Fig. 4, is a top plan view of the roller-supporting 40 block, showing the lamp wire terminals and wires connected therewith. Fig. 5, is a sectional view on the line 5—5 of Fig. 2. Fig. 6, is a sectional view on the line 6—6 of Fig. 2. Fig. 7, is a perspective view of the roller- 45 supporting block. And Fig. 8, is a side elevation, showing the manner of connecting the drop light and weight with the supporting fixture.

Referring to the accompanying drawings, 50 the numeral 1, indicates the ceiling plate, which is circular in form and made of suitable non-conducting material, preferably porcelain. The plate is constructed with a depending annular rim or lip 2, which forms 55 a circular recess or depression 3, in the center of the plate. The plate is secured to

the ceiling by screws, which pass through holes 4, at the bottoms of counter-sunk recesses 5 in the annular lip. At diametrically opposite points on the face of the lip, recesses 6 are formed, in which lie metal terminals 7, the depth of the recesses being the same as the thickness of the terminals, so that they will lie flush with the face of the lip. The terminals are secured to the ceiling plate by screws 8, which extend through holes in the plate and into threaded apertures in the terminals. The heads of these screws lie in counter-sunk recesses 9, in the back of the plate, which recesses are filled 60 with a suitable cement which prevents accident through contact with the head of the screw. The terminals are bent to form two horizontally disposed members, which are connected by a vertical member, which lies 65 against the inner surface of the annular lip. One horizontal member of each terminal is secured to the face of the lip while the other horizontal member rests upon the bottom of the circular depression 3, and is provided 70 with a threaded aperture, which receives a binding screw 10, the screws passing into recesses 11 in the plate. Oppositely positioned grooves or recesses 12, are formed in 75 the face of the annular lip, in line with each binding screw 10, and these recesses receive the ends of the circuit feed wires 13, which are secured to the terminals, by the binding screws 10, as shown in Fig. 3. The grooves or recesses 12, are employed when the plate 80 is connected with outside feed wires, but when the plate is connected with concealed feed wires, the said concealed wires pass through holes 14, in the plate, and thence to the terminals. Threaded holes 15 are 85 formed adjacent to the outer ends of the feed wire terminals 7, and these holes receive screws 16, the purpose of which will 90 presently appear.

The roller supporting block 17, which 95 forms the lower half of the fixture, is also made of suitable non-conducting material, preferably porcelain, and is of the form shown in the drawings. The upper face 100 of the block is flat and is provided with a central semi-circular chamber 18, of suitable depth, the sides of which are straight and parallel, and are formed with oppositely positioned grooves or recesses 19, which form 105 bearings for a pin 20, upon which is loosely 110 mounted a grooved roller 21, of non-conducting material, which lies within the

chamber 18, but so as to extend slightly above the face of the block. Holes 18^A are formed through the bottom of the chamber 18, in line with the grooved face of the roller 21. Terminals 22, are secured in diametrically opposite recesses 23, in the face of the block, by screws 24, which pass up through holes in the block, and enter threaded holes in the said terminals. The inner ends of the terminals 22, are provided with threaded holes which receive binding screws 26, and the outer ends thereof are slotted, as shown, one of the terminals having a slot 27, which extends in from one of its side edges, while the other terminal has a slot 28, which extends in from its end. In securing the block to the ceiling plate, the block is placed so that the terminal having the slot 28 engages one of the screws 16, of the terminal 7, the screw being withdrawn far enough to allow the said terminal 22 to pass between the terminal 7, and the head of the screw 16—the screw passing through the slot 28; the block is then turned until the opposite screw 16 engages the slot 27, in the other terminal 22, and both of the screws 16 are turned until their heads clamp the terminals 22 against the terminals 7, when the block will be securely held upon the plate. The face of the block is formed with a semi-circular groove 29, the ends of which terminate in line with the binding screws 26, and a hole 30 extends from the bottom of this groove through the block. Lamp wires 31 are passed through the hole 30, and one of them is clamped to the adjacent terminal 22 by its binding screw 26, while the other wire, which lies within the groove 29, is connected to the opposite terminal 22 by its binding screw 26. By reference to Fig. 5, it will be seen that when the block and ceiling plate are connected, the terminals 7 and 22 contact, and in this way the current from the feed wires passes from the terminals 7 to the terminals 22, and thence to the lamp wires. The lamp wires extend down from the block to and around a grooved roller 32, secured within a casing 33, containing a counter-balancing weight 34, through the center of which a short tube 35 extends. After passing around the roller 32, the lamp wires extend up through one of the holes 18^A in the block, and around the roller 21 through the other hole 18^A, and thence down through the tube 35 to the lamp socket 36, which is provided with the usual key for opening or closing the circuit to the lamp. The lamp and its fixtures are balanced by the weight 34, so that when the lamp is moved up or down to any desired point, it will remain stationary until moved again.

In operation, the ceiling plate is first secured in place, and the feed wires are connected to the terminals 7 by the binding screws 10. The lamp wires are then con-

nected to the block in the manner described, being first passed through the weight 34, and over the rollers 21 and 32. The block is then secured to the ceiling plate by the screws 16, which clamp the feed wire terminals 7 and the lamp wire terminals 22, together, which arrangement permits the current to pass from the feed wires to the lamp wires through the terminals. The lamp, weight, and supporting fixture are then in operative order, and the lamp may be adjusted to any desired point, and will be held at that point by the weight.

The arrangement and construction of the fixture is such that the parts may be quickly connected and disconnected, and the liability of short circuiting is eliminated.

Having described the invention, what I claim as new and desire to secure by Letters Patent, is:

1. In a fixture of the character specified, a non-conducting plate having circuit feed wire terminals; a non-conducting block having lamp wire terminals, said block having a semi-circular groove, the ends of which terminate adjacent to said terminals, and also a hole extending from said groove through the block, and a chamber having apertures at opposite points extending through the block; a grooved roller in said chamber, and means for securing the block to the plate so that the terminals of said block and plate contact.

2. In a fixture of the character specified, the combination with a non-conducting plate, having circuit feed wire openings and terminals adjacent to the openings having binding screws, of a non-conducting block having therein a centrally disposed semi-circular chamber with bearing recesses in its side walls, a semi-circular groove in the face of said block, a hole extending from said groove through the block and a hole through each end of the chamber; a pin in the bearing recesses of the chamber, a non-conducting grooved roller in said chamber mounted on the pin; lamp wire terminals upon the block having binding screws in line with and adjacent to the ends of the semi-circular groove, said terminals being extended beyond the sides of the block and provided with slots in their ends; and screws which pass through the said slots and into threaded holes in the feed wire terminals to clamp the block to the plate and cause the feed wire and lamp wire terminals to contact.

3. In a fixture of the character specified, the combination with a non-conducting plate having terminals adapted to be connected to circuit feed wires, of a block having terminals adapted to be connected to lamp circuit wires, and means for connecting the lamp wire terminals in contact with the feed wire terminals; a non-conducting

grooved roller mounted in a chamber in the block, said chamber having holes in line with the grooved face of the roller, a semi-circular groove being formed in the face of the block connecting the terminals, said block having a hole therethrough which intersects the groove.

4. In a fixture of the character specified, the combination with a non-conducting ceiling plate having terminals adapted to be connected with circuit feed wires; of a removable block provided with lamp wire terminals in contact with the feed wire terminals, and having a semi-circular groove 15 in its face extending from one terminal to the other, said block having also a hole therethrough which intersects the groove; a grooved, non-conducting roller in a chamber in said block, the chamber having oppositely disposed apertures in line with the grooved face of the roller; and screws for connecting the lamp wire and feed wire terminals.

5. The combination with a lamp and a counter-balancing weight, having a grooved roller, of a non-conducting ceiling plate having terminals adapted to be connected with circuit feed wires; a non-conducting block secured to the plate having terminals 25 in contact with the feed wire terminals; a non-conducting grooved roller mounted in

the block; and circuit wires connected to the lamp, which extend through the weight and around the roller in the block, thence around the weight roller to the terminals upon the block.

6. In a device as specified, the combination with a lamp, a counter-balancing weight having a grooved roller, and a ceiling plate, having terminals adapted to be connected with circuit feed wires, of a circular non-conducting block secured to the plate, having terminals in contact with the feed wire terminals; a non-conducting grooved roller mounted in a chamber in said block, the 40 block being provided with a concentric semi-circular groove which extends from one terminal to the other; said block having also a hole extending from said groove through the block; and circuit wires connected with the block terminals, which extend around the semi-circular groove and through the hole in said groove to and around the weight roller, thence over the block roller and down through the weight to the said lamp.

50 In testimony whereof I affix my signature in presence of two witnesses.

HARRY WALLACE LAWRENCE.
